UNITED STATES PATENT OFFICE.

CARLEY GOULD WELD, OF NORTH CHATHAM, MASSACHUSETTS.

AUXILIARY CARBURETER.

1,264,464.

Specification of Letters Patent. Patented Apr. 30, 1918.

Application filed August 23, 1913. Serial No. 786,216.

To all whom it may concern:

Be it known that I, CARLEY GOULD WELD, a citizen of the United States, residing at North Chatham, in the county of Barnstable 5 and Commonwealth of Massachusetts, have invented certain new and useful Improvements in Auxiliary Carbureters, of which the following, taken in connection with the accompanying sheet of drawings, forms a 10 full, clear, and concise description.

The present invention relates generally to improvements in means for supplying a combustible mixture to internal combustion engines and particularly to the starting of the 15 engine as hereinafter described.

The principal object of the present invention is the provision of means acting auxiliary to the carbureter whereby a properly proportioned rich and thoroughly vaporized 20 combustible mixture will be delivered to the cylinder or cylinders of the engine for the initial or starting impulse and until the engine assumes its normal condition of operation.

25 A further object of my invention is to provide a device as aforesaid which will cause the engine to start more easily and enable it to pull a load from its initial impulse which is frequently impossible under existing conditions where the carbureter alone must be 30 depended upon for the proper mixture.

35 My invention further comprehends a manually operated device which will effect a saving in fuel and permit of a finer or closer adjustment of the carbureter; which will be simple in construction and may be economically manufactured and assembled, and which may be readily attached to and made a part of the power-plant of which an internal 40 combustion engine is the power unit.

Various other objects and advantages of my device will be apparent as the description proceeds.

Briefly stated, my invention comprises an auxiliary carbureter which communicates with the float chamber of the main carbureter and with the intake pipe of the engine and by the arrangement and operation of its parts as hereinafter set forth will thoroughly 50 vaporize the mixture passing thereto from the float chamber of the carbureter and deliver a rich full charge to the engine cylinders.

I will now proceed to describe my invention with reference to the accompanying drawings wherein, for the sake of clearness

I have shown my invention as applied to a motor vehicle power plant, though I would have it understood that it is equally applicable to any form or type of power plant employing an internal combustion engine, the essential elements of novelty being more particularly set forth in the appended claims.

In the drawings:

Figure 1 is a diagrammatic view showing the relative position of any device to the engine and main carbureter, and

Fig. 2 is a sectional elevation of my device showing its relation to the main carbureter, a fragment of the latter being illustrated.

Referring now to the drawings in detail, in which like characters of reference are employed to designate similar parts throughout the several views, 7 indicates an internal combustion engine of the four-cylinder type having the usual cooling and fuel supply systems, the main carbureter being indicated by the reference character 8.

Communicating with each of the engine 80 cylinders is the usual intake or supply pipe 9 connected to the carbureter 8 and delivering fuel to the cylinders in the well known manner, the fuel level within the carbureter being indicated by the dotted line a—a. 85

The auxiliary carbureter 10 is preferably mounted adjacent to the main carbureter 8, as shown, in a position whereby the gasoline or fluid level indicated by the dotted line a—a will be common to both the main carbureter and the auxiliary carbureter. To cheapen the cost of manufacture and facilitate assembling, I have found it desirable to make the auxiliary carbureter in three parts or sections, the main or body section 95 being indicated by 11 and the upper and lower section threaded thereinto numbered 12 and 13 respectively. The outer ends of the upper and lower sections are preferably formed with nipples to receive standard connection or copper tubing whereby the auxiliary carbureter has communication with the engine 7 and the main carbureter 8, the connection 13^a leading from the upper end of the auxiliary carbureter 10 to the highest 105 point in the intake pipe 9 common to all of the cylinders of the engine 7, the lower end of the auxiliary carbureter being connected to a pipe or tubing 14 opening into the float chamber of the carbureter 8.

The body or main section 11 of the auxiliary carbureter 10, is provided with a cen-

2

tral bore or passageway 15 extending vertically thereof, this passage-way communicating with a vertical bore 16 in the upper section 12 and also with the passage 17 in the lower section 13, as and for the purposes which will be hereinafter explained. A lateral bore opening into the passage 15 and indicated by the reference numeral 18, is provided in the central section or portion 11, a sleeve 19 being threaded into said member contiguous to said lateral bore and providing a housing or seat for the plunger valve 20 which is adapted to be maintained in open position as shown in Fig. 2, against the tension of the spring 21, by any suitable manual means, such as a chain or cable 22 having a connection with a pedal 23 or a lever or the like, located on the dash-board of the vehicle, this pedal being adapted to be locked by a spring catch 24 to hold the plunger in open position.

It will be observed from the structure thus far described and shown, that when the plunger 20 is locked in open position there will be an uninterrupted passage-way between the passages 15 and 16, the lower portion of the bore 15 in the central or body portion 11 being enlarged to provide a seat for the spring seated valve 25. This valve 25, under the tension of the spring 26 closes the chamber 27 formed therebelow, with which the air ports 28 have communication and through which fresh air is drawn into the auxiliary carbureter, as will hereinafter be apparent. 29 is a needle valve for regulating the supply of gasoline from the float chamber of the carbureter 8, the gasoline passing through the passage 17 and through the preferably obliquely disposed ducts 30 communicating with the enlarged portion of the passage-way 15, in the central or body section 11.

In the operation of my invention, the main carbureter 8 and the ignition system of the engine 7 are adjusted for the operation of the engine in the customary manner, the plunger valve 20 being opened by means of the chain 22 and pedal 23, as heretofore described, after which the engine is "turned over," the movement of the pistons within the engine cylinders creating a suction which, through the medium of the intake pipe 9 and the connecting pipe 13^a, causes the ball valve 31 to rise, and also raises the valve 25 against the tension of the spring 26. This operation draws in a quantity of fresh air through the ports 28 and simultaneously sucks up the gasoline or other fluid from the float chamber of the carbureter and through the connecting pipe 14 and the passage-way 17, the gasoline or the like passing through the ducts 30 and combining or mixing with the air within the passage-way 15, and forming a rich and thoroughly vaporized mixture which flows past the ball valve 31 and

through the passage-way 16 of the upper section 12 to the engine cylinders, through the medium of the connecting pipe 13^a and the intake pipe 9, a properly proportioned charge being delivered to each cylinder by reason of the fact that the connecting pipe 13^a enters the intake pipe 9 at its highest point so that the distribution of the mixture is common to all of the cylinders.

I have found that the mixture delivered by my auxiliary carbureter in the aforesaid manner is properly proportioned, and that a high efficiency is obtainable therefrom, the initial impulse of the engine taking place with comparative ease, and enabling the engine to start under a load which is frequently impossible where the main carbureter only is employed.

Should there be a back pressure owing to misfiring of the engine, or from any other cause, the vaporized mixture which has passed through the auxiliary carbureter cannot return thereto owing to the provision of the ball valve 31, which under the force of such back pressure becomes firmly seated within the lower reduced portion of the passage-way 16 in the upper section 12. When the engine assumes its normal condition of running, the pedal 23 is released by the manipulation of the catch 24, which causes the plunger valve 20, under the impulse of the spring 21, to close the passage 15 the valve 25 simultaneously returning to its normal seated position under the influence of the spring 26, and closing the chamber 27 communicating with the air ports 28. The provision of the adjustment or needle valve 29 enables me to minutely regulate the supply of gasoline or other liquid delivered to the chamber 15 for vaporization so that I may obtain the highest starting efficiency with the least possible consumption of fuel.

While I have described my invention with particular reference to the embodiment herein shown and described, it is obvious that it is adaptable to other uses, wherever an internal combustion engine is employed, and that various changes in the details of structure may be made without departing from the spirit and scope of my invention.

Having thus described my invention on what I claim as new herein and desire to secure by Letters Patent is:

1. An auxiliary carbureter for internal combustion engines adapted to be connected to the intake pipe and the float chamber of the main carbureter, said auxiliary carbureter embodying a central longitudinal bore, a back-pressure check valve seated therein, fresh air ports located in the wall of said auxiliary carbureter and arranged for communication with said bore, a valve located in said bore to cut off said ports from communication with said bore and means for rendering said auxiliary carbureter opera-

- tive whereby the initial operation of the engine will draw a quantity of fuel and fresh air into said central bore and effect a mixture of said elements therewithin.
- 5 2. In combination with an internal combustion engine having a manifold and a main carbureter, an auxiliary carbureter connected to said manifold and to the float chamber of said carbureter, said auxiliary carbureter being provided with a central longitudinal bore, a plurality of fresh air ports positioned in the wall of said auxiliary carbureter and arranged to communicate with said bore, a valve mounted within 10 said bore, means for normally seating said valve to close the communication between said ports and said central bore, means normally operating to close communication between two portions of said bore, said means 15 being capable of manual operation to open said bore whereby upon the initial movement of said engine, a quantity of fresh air will be drawn in through said ports, and a quantity of fuel sucked in from the float chamber of 20 said carbureter, past said valve and form a mixture within said bore and flow into said manifold; and means positioned within said bore for preventing a back pressure within 25 said central bore.
- 25 3. In combination with an internal combustion engine, having a manifold and a carbureter, an auxiliary carbureter connected to said manifold and to the float chamber of said carbureter, said auxiliary carbureter being provided with a central longitudinal bore, a lateral passage opening into said bore, means operating within said passage to normally close said bore, a plurality of air ports arranged to communicate with said bore to 30 deliver fresh atmospheric air thereto, a valve seated in said bore and arranged to normally close communication between said bore and said ports, and manually controlled means for functioning said auxiliary carbureter whereby upon the initial operation of said engine, fresh air and fuel will be drawn into 35 said central bore and a highly combustible mixture delivered to said manifold; and means for preventing a backward flow of the mixture through said central bore. 50
4. In combination with an internal combustion engine having a manifold and a carbureter, an auxiliary carbureter connected to said manifold and to the float chamber of said carbureter, said auxiliary carbureter being provided with a central longitudinal bore, a lateral passage opening into said bore, means operating within said passage to normally close said bore, a plurality of air ports arranged to communicate with said bore to 55 deliver fresh atmospheric air thereto, a valve seated in said bore and arranged to normally close communication between said bore and said ports, and manually controlled means for functioning said auxiliary carbureter whereby upon the initial operation of said engine, fresh air and fuel will be drawn into said central bore and a highly combustible mixture delivered to said bore, and means for preventing a backward flow of the mixture through said central bore. 60
- 55 In witness whereof I have hereunto set my hand in the presence of two subscribing witnesses this 20th day of August, 1913.
